(57) **CLAIM**

The ornamental design for a broom housing assembly, as shown and described.

DESCRIPTION

FIG. 1 is a top perspective view of a broom housing assembly, and a handle shown in phantom;

FIG. 2 is a front elevation view of the broom housing assembly illustrated in FIG. 1, with the handle shown in phantom;

FIG. 3 is a rear elevation view of the broom housing assembly illustrated in FIG. 1, with the handle shown in phantom;

FIG. 4 is a top view of the broom housing assembly illustrated in FIG. 1, with the handle shown in phantom;

FIG. 5 is a bottom view of the broom housing assembly illustrated in FIG. 1, with the handle shown in phantom;

FIG. 6 is a left end view of the broom housing assembly illustrated in FIG. 1, with the handle shown in phantom; and,

FIG. 7 is a right end view of the broom housing assembly illustrated in FIG. 1, with the handle shown in phantom.

The broken line showing of a handle illustrates environmental structure that forms no part of the claimed design. The bristles, which are understood to be closely packed, are partially shown for ease of illustration.
